DOOR KNOB

Van Day Truex, New York, N. Y., assignor to The Yale & Towne Manufacturing Company, Stamford, Conn., a corporation of Connecticut

Application April 30, 1956, Serial No. 41,249

Term of patent 7 years

(Cl. D50—3)

Fig. 1.

Fig. 2.

Fig. 1 is a face view of a door knob, showing my new design.

Fig. 2 is a top plan view of Fig. 1.

The characteristic feature of the door knob resides in the ornamental pattern on the face thereof.

I claim:

The ornamental design for a door knob, substantially as shown and described.
